UNITED STATES PATENT OFFICE.

ALEXANDER H. WOOD, OF KILDAV, KENTUCKY, ASSIGNOR TO WOOD EQUIPMENT COMPANY, OF CHICAGO, ILLINOIS, A CORPORATION OF ILLINOIS.

SYSTEM FOR STORING BULKY MATERIALS.

1,300,800.

Specification of Letters Patent.

Patented Apr. 15, 1919.

Application filed July 2, 1917. Serial No. 178,248.

To all whom it may concern:

Be it known that I, ALEXANDER H. Wood, a citizen of the United States, residing at Kildav, in the county of Harlan and State 5 of Kentucky, have invented new and useful Improvements in Systems for Storing Bulky Materials, of which the following is a specification.

This invention relates to improvements 10 in systems for handling bulky material such as coal, ore, crushed rock, sand, gravel, etc., and more especially to an improved system for storing such material in a storage space in such manner that it may be readily 15 accessible for removal whenever desired, and for removing the material whenever any of it is needed.

The invention is designed particularly to provide a practical and economical method 20 of storing coal so that it may be removed from coal cars, boats or other agencies of transportation, and stored in a pile on the ground, with means for simply and economically taking up the coal from storage 25 and delivering it back into bins, cars, boats or the like whenever any of it is required.

The invention briefly described contemplates a power shovel or crane, commonly called a locomotive crane, operating on a 30 semi-circular track and picking up the coal or other material from the coal cars, boat or hopper into which it has been dumped at a point in the center of the semi-circle the crane then swinging around and depositing 35 its load into the hopper of a revolving, portable conveyer which operates on a concentric semi-circular track some distance beyond the first track; the conveyer in turn carrying the coal out to the farthest extent 40 of its reach and depositing it over the entire area which may be covered by it, including the space beyond the outer track and between the two tracks and even the space occupied by the tracks themselves; the two 45 machines burying their tracks as they move along, as will be hereinafter described. When all of the area which is available through the operation of the conveyer has been filled the locomotive crane working on 50 the inner track will proceed to fill up the remaining space, whereupon the maximum storage capacity is reached. For removing the material from storage the locomotive

crane first digs out the inner track and the semi-circular space within it, then the conveyer is transferred to its track, and the locomotive crane placed on the outer track to pick up the coal beyond the outer semi-circle and deliver it to the conveyer, whence it is carried inward and discharged into cars 60 or other carriers, or into a hopper.

A complete system embodying the principles of the invention is illustrated diagrammatically in the accompanying drawings in which:

Figure 1 is a plan view showing the complete system.

Fig. 2 is a vertical section on the line 2—2 of Fig. 1.

Fig. 3 is a view in end elevation showing my improved revoluble and portable conveyer which constitutes one of the parts of the system.

As shown in said drawings, the system illustrated is designed more particularly for 75 the storage of coal and similar material and accordingly there are provided a pair of railroad tracks, 10, 10, which are here shown merely diagrammatically and may be a part of the regular railroad system by means of 80 which coal is brought to the storage place and discharged into a pit or hole in the ground, 11. About the pit 11 as a center is arranged a semi-circular piece of track, 15, which may preferably include four rails 85 to provide better stability for a locomotive crane, 16, which is designed to operate on the track. The locomotive crane includes a car or truck, 17, which carries suitable machinery to operate a boom, 18, with a "clam shell" or other suitable bucket, 19, at its end, the machinery being housed in a structure, 20, which is mounted on a circular row of wheels, 21, on the car platform so that the boom can revolve in a horizontal circle. 95 The entire piece of apparatus herein designated as a locomotive crane is well known in the art and in lieu of the particular device herein illustrated and described, there may be substituted a similar piece of apparatus made in any approved manner, as the particular design or construction of the locomotive crane does not constitute any part of the present invention.

Beyond the semi-circular track 15 there 105 is arranged a parallel piece of track, 30,

on which is shown a piece of apparatus herein designated as a revoluble, portable conveyer. The latter comprises a car or truck, 35, arranged to provide a horizontal platform, 36, over which is mounted, on a circular row of wheels, 37, a revoluble structure 38, housing the driving machinery and parts of the operating mechanism. Extending from one side of the structure 38 is a long boom, 45, which is hinged on a horizontal pivot, 46, at its inner end so that its outer end may be raised and lowered through a chain or cable, 49. The boom 45 supports an endless link belt or conveyer, 50. At the opposite side of the structure 38 from the boom 45 is a receiving hopper, 55, through which material may be delivered upon a horizontal section of conveyer, 57, whence it is carried to the foot of the conveyor 50 and thence up the latter and spilled over its end. As all of the elements of the mechanism of this piece of apparatus, such as the car or truck 36 with wheels to roll on the track 30, means for driving the wheels to propel the truck, the circular row of supporting wheels 37, suitable propelling and driving machinery to propel the apparatus on its track, to operate the conveyer, to raise and lower the boom, and to revolve the apparatus on its vertical pivot, are well understood, the actual details of construction of this apparatus are not herein shown, and the illustration is merely diagrammatic, but it is believed to be sufficient to enable any one skilled in the art to which it appertains to construct a machine which will perform the functions herein described.

In addition there is provided at the adjacent ends of the two semi-circular pieces of track 15 and 30, a transfer table, 60, on a connecting piece of track, 62, whereby the two machines 16 and 38 may be transferred from one track to the other, and a section of track, 65, extending beyond the end of one of the semi-circles, to receive one of the machines and thus permit them to pass each other.

The operation of the complete system is as follows:

The coal or other material having been brought to the storage grounds along the adjacent track 10 and dumped into the pit 11, the crane 16 is operated on the inner semi-circular track to pick up the coal out of the pit, swing it around and discharge it into the hopper of the conveyer 38, which latter operates on the outer semi-circular track and carries the coal out to the farthest extent reached by its boom. In this operation the conveyer boom is first lowered so as not to drop the coal any farther than necessary, as it is desirable to avoid breaking the coal as much as possible; and in this manner the entire available space beyond the outer track, the semi-circular strip between the two tracks, 65 and the area occupied by the track 30 itself

may be filled up; the two machines starting at the ends of the two tracks farthest from the two transfer tables and working around toward the latter. As the two machines proceed thus the locomotive crane can also bury its own track behind it, and can even fill the semi-circular space included within its track. When the storage space is all filled up the two machines may remain on the transfer table or the connecting track, 62 until required for removing the coal from storage; and this operation is accomplished by first operating the locomotive crane 16 on the inner track 15 to clear the latter, the space within it, and as much space between the two semi-circular tracks as can be reached by the boom 18; and then the two machines are switched about and the locomotive crane 16 placed on the outer track 30 and operated to pick up the coal from the remaining storage space and drop it into the hopper of the conveyer 38, which latter is operated on the inner track 15 to carry the material inward and load it into cars on the track 10, or into a hopper or bin.

It will thus be seen that with the operation of the two machines together in either the storing of the coal or its removal from storage the operation is practically continuous, the only shifting about of the mechanism required being the swinging around of the boom of the locomotive crane to carry the material picked up by it around in an arc and deposit it into the hopper of the conveyer, which latter can operate uninterruptedly to carry the material on farther and discharge it over its end. The only additional operation required is the occasional moving of the machines, and there is thus rendered available for storage a much greater area than could practically be reached by the boom of any single piece of apparatus, and with a great saving in time over any system or process which requires picking up the material by a machine and depositing it on the ground and then moving the machine about and picking the material up by the same machine again. Equally wasteful and uneconomical is any system which requires a machine to pick up material, then to propel itself with its load to another point to discharge the material and then to go back empty for another load.

All of the foregoing objections are removed in the system above described, and without departing from the spirit of the invention the system might be modified in many respects, such as supplying the coal or other material to the dumping pit 11 by boat, or other carrier, instead of by cars; or by providing a second set of semi-circular tracks on the other side of the railroad tracks 10, 10, thus making the storage grounds substantially a circle instead of a semi-circle; and the features of design of the two pieces

of apparatus 16 and 38 might be considerably changed without materially modifying their functions, as above set forth.

I claim as my invention:

- 5 1. In a system for storing material, the combination with a locomotive crane operating on a track and adapted to pick up material deposited on one side of the track, of a parallel track on the opposite side from the material and a portable conveyer operating on the second track and adapted to receive material from the locomotive crane and deposit it beyond the second track, the conveyer having a boom adapted to revolve in a horizontal plane, whereby material may be stored beyond and between the tracks and
- 10
- 15

upon the track beds, and may be removed therefrom.

2. In a system for storing material, the combination with two curved parallel 20 tracks, of a locomotive crane on the inner track adapted to pick up material and convey it to a portable conveyer on the outer track, the portable conveyer having a boom adapted for raising and lowering and for 25 swinging in a horizontal plane, whereby material may be stored beyond and between the tracks and upon the track beds, and may be removed therefrom.

In witness whereof, I have hereunto subscribed my name this 20th day of June, 1917.

ALEXANDER H. WOOD.
